(57) CLAIM

(21) Appl. No.: **29/191,343**

The ornamental design for a pillow cover for steering wheel,
as shown and described.

(22) Filed: **Oct. 6, 2003**

DESCRIPTION

(51) LOC (7) Cl. **12-16**

FIG. 1 is a front elevational view of a pillow cover for

(52) U.S. Cl. **D12/177**

steering wheel showing my new design;

(58) Field of Search **D12/175-177;**
74/558, 558.5; 280/750

FIG. 2 is a rear elevational view thereof;

FIG. 3 is a side view, taken from the left side of FIG. 1, the
right side, top plan and bottom plan views being the same
thereas; and,

FIG. 4 is a rear perspective view thereof.

The dotted lines showing a steering wheel in phantom are for
illustrative purposes only and form no part of my claimed
design.
